(57) **CLAIM**

The ornamental design for a board game tier, as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever. This patent is related to U.S. Design application Ser. No. 29/484,598, titled, "Board Game Tile", filed Mar. 11, 2014. FIG. 1 is a perspective view of a board game tier.

FIG. 2 is a front side elevation view thereof.

FIG. 3 is a rear side elevation view thereof.

FIG. 4 is a top plan view thereof.

FIG. 5 is a bottom plan view thereof.

FIG. 6 is a right side elevation view thereof; and,

FIG. 7 is a left side elevation view thereof.

The broken line showing of side edges is included for the purpose of illustrating portions of the "article" and forms no part of the claimed design.
